UNITED STATES PATENT OFFICE.

JOSEPH W. SHARP, JR., OF PHILADELPHIA, PENNSYLVANIA, ASSIGNOR TO HAINES,
JONES & CADBURY, INC., OF PHILADELPHIA, PENNSYLVANIA, A CORPORATION OF
PENNSYLVANIA.

WATER-CLOSET.

1,218,124.

Specification of Letters Patent. Patented Mar. 6, 1917.

Application filed November 8, 1910. Serial No. 591,353.

To all whom it may concern:

Be it known that I, JOSEPH W. SHARP, Jr., a citizens of the United States, residing at Philadelphia, in the county of Philadelphia and State of Pennsylvania, have invented new and useful Improvements in Water-Closets, of which the following is a specification.

The present invention relates to water closets, and particularly to that type of closets known as "vented closets," so called because provision is made for venting the bowl by way of a suitable flue, this bowl ventilation giving also a ventilating result in the room in which the closets are installed, both bowl and room ventilation being secured by means of a suitable vent passage which leads from the bowl proper to the flue adjacent which the closet may be located.

It has for its object to provide a bowl construction in which the venting passage is conveniently and efficiently placed, so that its molding in the ware may be readily accomplished, and its efficiency so far as venting results are concerned will be high; the arrangement being such that flue connections may be conveniently made and at the same time flooding and fouling of the flue will be avoided.

In the embodiment of my invention herein shown I have illustrated various forms to show the different physical expressions of my invention, although it will be understood that the same principle underlies the several forms of the invention here exhibited.

In the drawings which accompany and form a part of this specification—

Figure 1 is a sectional view of so much of a closet bowl as will illustrate my invention.

Fig. 2 is a plan view of the closet shown in Fig. 1, illustrating in dotted lines the arrangement of passages.

Figs. 3 and 4 are sectional views illustrating embodiments of my invention other than those found in the figures hereinbefore referred to.

Figs. 5, 6 and 7 are sectional views of bowls to illustrate other developments of my invention to which reference will be made in the detailed description which follows.

Referring now to the drawings by numerals, and first to Fig. 1, B indicates a bowl having any suitable supply spud and siphon passage, the supply spud giving the necessary water to the bowl and rim by the duct

b and rim passage *b'*, both shown in dotted lines.

Traversing the upper portion of the bowl is a vent passage *b*² which connects the bowl proper with a suitable vent pipe *b*³ delivering to a suitable flue (not shown) in the rear of the closet. The vent passage *b*² is laid between the supply ducts *b* which lead from the spud at the top of the bowl, and said vent passage passes over the top of the siphon passage, as shown.

The vent pipe *b*³ is shown in Fig. 1 as an independent pipe coupled by a suitable connection with the rear of the closet, a similar coupling being provided at the rear end of said pipe *b*³ by which it is connected to the wall of the vent flue. Said vent pipe *b*³ has a slot or aperture *b*⁴ formed in its underside, which slot *b*⁴ has the double function of providing direct ventilation from the room to the flue in addition to the ventilation which takes place through the bowl and vent passage *b*², thus preventing any flooding or fouling of the flue in event of the choking of the bowl, for it is obvious that should the bowl fill and the contents make back into the vent passage *b*², the slot *b*⁴ in the vent pipe *b*³ would effectually drain to the floor and no contamination of the flue could occur.

It will be observed that the slot *b*⁴ is located near the inner end of the pipe *b*³ so that a sufficient working length is left for the plumber at the outer end of the pipe to make such cuts and wall connections as may be necessary in setting the closet without interfering with the vent slot *b*⁴.

The vent passage *b*² of the closet lifts upwardly, as shown, and has a wall or dam *b*⁸ (see Fig. 1) which rises to or above the level of the bowl rim, which dam *b*⁸ while it does not interfere with the venting action guards against flooding the vent passages and the flue because of the fact that the bowl contents will overflow the bowl rim before they can pass the dam *b*⁸, thus giving a safe guard additionally to the slot *b*⁴ in the vent pipe *b*³ against flooding the vent passages and flue.

In order that a proper wash of the vent passage and dam face may be given at each flush of the closet, I provide a connection from the spud at the top of the closet, said connection comprising a chamber *b*⁵, which, when the flushing valve of the closet is

pulled, receives water from the spud connection, and, by suitable apertures b^6 delivers it directly upon the face of the dam b^6 , insuring its frequent and complete cleansing.

5 Preferably I drop a web or apron b^7 forward from the raised spud receiving portion of the closet, so that the receding aperture of the vent passage b^8 is to a considerable extent concealed.

10 The dam in the vent passage is formed by the upper wall of a refill chamber, as shown, which refill chamber is located in the usual manner at the bend of the siphon passage and so formed as that its wall b^8 extends above the level of the bowl and effectually dams the vent passage.

15 Instead of forming the raised back, as shown in Fig. 1, namely, with a forwardly 20 extending web, I may extend the chamber which receives its flushing water from the spud supply forwardly, as shown in Fig. 3, so that a raised stop is provided which gives a chamber C of sufficient capacity to properly flush the vent passage wall c , suitable apertures c' being provided through which the wall-flushing jets may act.

25 In the form shown in Fig. 4, the dam in the vent passage is formed by the upper 30 wall of the refill box C', the upper wall of this refill box extending upwardly, as shown, into the vent passage, above the top of the bowl, the raised back of the bowl having the forwardly and downwardly extending web 35 as shown, and being provided also with a washing chamber C² which connects by a suitable orifice c^2 with the supply spud, delivery orifices c^3 being formed in the bottom of the chamber C², so as to furnish a washing 40 supply for the sloping face of the vent passage dam as it leads to the bowl.

45 In Fig. 5, I have shown a raised back closet in which the stop at the rear of the bowl is slightly different in form, said stop 50 D having the vent passage d passing through it with the forward end at an angle to the bowl rim shown, so as to present a good venting orifice to the bowl, the said passage d passing rearwardly between the ducts d' (see dotted lines) leading from the supply spud, and above a refill chamber d^2 , said refill chamber having the refill apertures d^3 , as shown. It will be seen that the top of the 55 refill-chamber d^2 extends above the bowl rim, so as to dam the vent passage d effectually against flooding.

60 In Fig. 6 a very similar construction to that found in Fig. 5 is disclosed, except that the vent passage E passes below the refill chamber e , a raised dam e' similar to those heretofore described being provided which will prevent back-flow from a choked bowl; said refill chamber e having apertures e^2 which are so arranged as to wash the wall of 65 the vent passage which slopes to the bowl

and keep it in sanitary condition, and to supply wash for the rear of the bowl in lieu of the regular flush rim, which does not extend around the rear of the bowl.

6 In Fig. 7, I have shown the vent passage F as passing upwardly through the back-stop f and over the refill chamber f' , the top of which chamber dams the passage against flooding, said stop f being curved down and rearwardly so as to conceal the vent passage entrance, while the refill chamber f' , by suitable apertures f^2 delivers to the jet chamber f^3 from which the wall wash passes downwardly to the bowl.

75 10 In the forms of my invention heretofore described, I have shown the vent pipe which connects the closet to the flue as formed of metal and coupled to the back of the closet, such pipe having the vent slot formed in it. I have shown in Fig. 7 how, by extending 80 the ware of the closet back so as to give a neck f^4 , I may form the vent slot f^5 directly in the ware itself, the neck f^4 being connected in any suitable manner to the vent flue.

85 15 The closet which I have invented and which is exemplified in the various forms disclosed, is one which may be readily molded in the vitreous ware now commonly in use; which will not flood back into the flue if the bowl chokes; and which will give 90 always a proper ventilation of the bowl and room, not only through the bowl, but also through the direct venting slot of the flue connection.

95 100 Such variations in design and structure as are but mechanical variations of my invention, I regard as within its range, and this disclosure is, therefore, to be regarded as restricted only in so far as it is restricted by the terms of the claims herewith.

105 I claim:

1. A water closet bowl having the usual supply and siphon passages and provided with a ventilating duct leading directly through the ware over the bend of the siphon passage to the outside of the ware and having its inlet and outlet below the level of the bowl, an overflow preventing dam formed integrally with and projecting from the siphon bend to a point above 115 the top of the bowl, and means for flushing the dam.

2. A water closet bowl having the usual supply and siphon passages and provided with a ventilating duct leading through 120 the ware over the bend of the siphon passage and directly out through the back of the ware, said duct having its inlet and outlet below the level of the bowl, an overflow preventing dam formed integrally 125 with and projecting from the siphon bend above the top of the bowl, and a venting and draining aperture in the wall of said duct on the outlet side of said dam.

3. A water closet having a ventilating 130

duct, an overflow-preventing dam in said duct which extends above the level of the bowl, and flushing apertures in the wall of said duct which deliver to a wall of the 5 overflow preventing dam.

4. A water closet having a ventilating duct an overflow-preventing dam in said duct which extends above the level of the bowl, and flushing apertures in the wall 10 of said duct which deliver to the sloping wall of the overflow dam on the bowl side of said dam.

5. A water closet having a ventilating duct, an overflow-preventing dam in said 15 duct which extends above the level of the bowl, a flushing chamber connected with a suitable supply, and flushing apertures delivering from said chamber to the sloping surface of said overflow dam on the 20 bowl side thereof.

6. A water closet bowl having a ventilating duct, an overflow-preventing dam in 25 said duct which extends above the level of the bowl, a raised back on said bowl provided with a forwardly-extending abutment, and an apron on said abutment which extends below the level of the bowl over the inlet of said ventilating duct.

7. A water closet bowl having a ventilat-

ing duct extending rearwardly from the 30 top of the bowl, an overflow preventing dam in said duct, and a concealing apron extending down into the hopper below the level of the top of the bowl whereby to conceal the inner open end of the duct. 35

8. A closet bowl having the usual supply and siphon passages and provided with a ventilating duct leading directly through the ware over the bend of the siphon passage to the outside of the ware and having 40 its inlet and outlet below the level of the bowl, an overflow preventing dam formed integral with and projecting from the siphon bend into the ventilating duct to a point above the top of the bowl, and means 45 for flushing the inlet side of the dam into the bowl, said bowl having a vent and overflow slot at the base of the dam opening into the space about the bowl and adapted to drain off any overflow from the outlet 50 side of said dam.

In testimony whereof I have hereunto set my hand in presence of two subscribing witnesses.
